DESIGN FOR A METER CASING

Joseph A. Hayes, Camp Hill, Pa., assignor to
Neptune Meter Company, Long Island City,
N. Y., a corporation of New Jersey

Application November 21, 1936, Serial No. 66,065

Term of patent 14 years

To all whom it may concern:

Be it known that I, Joseph A. Hayes, being a citizen of the United States and a resident of Camp Hill, in the Commonwealth of Pennsylvania, have invented a new, original, and ornamental Design for a Meter Casing, of which the following is a specification, reference being had to the accompanying drawing forming a part thereof, in which:

Figure 1 is a plan view of a meter casing embodying the design of the present invention;

Figure 2 is a view in elevation of the meter casing illustrated in Figure 1; and

Figure 3 is an elevation taken at right angles to that of Figure 2, showing the meter casing of the present invention.

I claim:

The ornamental design for a meter casing, as shown.

JOSEPH A. HAYES.
